UNITED STATES PATENT OFFICE.

GENNARO APRILE, OF PROVIDENCE, RHODE ISLAND.

SURGICAL IRRIGATOR.

1,355,727.

Specification of Letters Patent.

Patented Oct. 12, 1920.

Application filed April 26, 1919. Serial No. 292,848.

To all whom it may concern:

Be it known that I, GENNARO APRILE, a subject of the King of Italy, residing at Providence, in the county of Providence and 5 State of Rhode Island, have invented new and useful Improvements in Surgical Irrigators, of which the following is a specification.

My present invention pertains to surgical apparatus for irrigating or flushing wounds in or cavities of the body and particularly to that kind of apparatus in which provision is made for the expeditious discharge of the irrigating or flushing fluid.

15 The object of my invention is to provide in an apparatus of the character set forth, a nozzle having longitudinal conduits so arranged relatively to the eduction orifice of the nozzle that the possibility of the said 20 orifice being obstructed by blood clots or any other solid or semi-solid particle is precluded.

With the foregoing in mind, the invention will be fully understood from the following 25 description and claim when the same are read in connection with the drawings, accompanying and forming part of this specification, in which:

Figure 1 is a view, partly in elevation and 30 partly in longitudinal section, showing the apparatus constituting the best practical embodiment of my invention that I have as yet devised.

Fig. 2 is an enlarged longitudinal section 35 illustrative of the novel nozzle comprised in the apparatus.

Fig. 3 is a transverse section taken in the plane indicated by the line 3—3 of Fig. 2.

Similar numerals of reference designate 40 corresponding parts in all of the views of the drawings.

Among other elements, my novel apparatus comprises a receptacle 1, designed to be held or supported in an elevated position and to be connected through a hose 2 with the arm 3 of the novel irrigating nozzle which as a whole is designated by 4. In addition to the arm 3, the nozzle 4 comprises an arm 5, and if desired a hose (not shown) may be attached to the arm 5 to conduct a flushing or irrigating fluid to any desired point of discharge. The arm 5 is arranged divergent to the arm 3, and the two arms are joined at their forward ends 55 to the body 6 of the nozzle. The said body

6 is of tubular form and is provided in its forward end with a contracted orifice 7.

Affixed in the body 6 and dividing the same into two longitudinal conduits 8 and 9 is a partition wall 10, the rear end of 60 which is disposed between and adapted to separate the inner ends of the arms 3 and 5. The forward end of the partition 10 is arranged in the tubular body 6 and is separated from the forward end of the said 65 body 6 and the contracted orifice therein by an intervening space 11, of about the proportional size illustrated.

In the practical use of my apparatus the nozzle body 6 is introduced into the wound 70 or cavity to be irrigated or flushed and the irrigating or flushing fluid is supplied to the receptacle which is indicated as held or supported in an elevated position. When this is done it will be observed that the 75 fluid will pass through the hose 2, the arm 3, the conduit 8, the space 11 and the orifice 7 into the wound or cavity, and coincident with or subsequent to the said flow of the flushing or irrigating fluid the said fluid 80 will pass from the wound or cavity through the orifice 7, the space 11 and the conduit 9 to a suitable point of discharge.

It will be manifest that coincident to the described use of the apparatus, the fluid 85 leaving the conduit 8 and the fluid entering the conduit 9 will cause agitation in the space 11, calculated to prevent any particle from obstructing the orifice 7 or the adjacent ends of the conduits 8 and 9. It will 90 also be manifest that the volume of fluid passing through the conduit 8 will effect the movement of any particle present in the space 11 to that side of the space adjacent to the entrance of the conduit 9, and consequently the particle can not operate to obstruct the communication between the forward end of the conduit 8 and the orifice 7. Again, in the event of a particle being present in the space 11 incidental to the 100 backward flow of fluid through the orifice 7 to the conduit 9, the fluid will operate to move the particle to that side of the space 11 adjacent to the forward end of the conduit 8, and consequently the particle will be 105 prevented from interfering with the flow through the space 11 between the orifice 7 and the adjacent end of the conduit 9.

My improvement is also adapted to be used to advantage in the treatment of vene- 110

real diseases of men, the nozzle 4 being, by reason of its exteriorly and forwardly tapered head and its contracted orifice 7, to be introduced into the urethra.

5 Having thus described my invention, what I claim and desire to protect by Letters Patent is:—

10 A nozzle for the purpose described having a tubular body with a contracted orifice in the forward end thereof, and also having at the rear end of the tubular body and in communication therewith divergent tubular arms, one of which is adapted to discharge fluid, a longitudinal partition sepa-

rating the inner ends of the arms and extending from the juncture thereof forwardly to a point in rear of and adjacent to the contracted orifice in the tubular body, whereby the tubular body is divided into two longitudinal conduits and a space is afforded 20 at the forward ends of said conduits between the said ends and the end orifice, and a head at the forward end of the tubular body exteriorly tapered forwardly to a point about the contracted orifice.

25 In testimony whereof I affix my signature.

GENNARO APRILE.
